UNITED STATES PATENT OFFICE

BURGESS T. SPRY, OF SAN DIMAS, CALIFORNIA

ADJUSTING LEVER FOR CULTIVATORS AND THE LIKE

Application filed November 22, 1929. Serial No. 409,045.

This invention relates to an adjusting lever for use in connection with cultivators and the like.

It is well known to those skilled in the art that when the cultivator is used in an orchard, the upstanding lever used for raising and lowering the soil engaging elements frequently becomes caught in the overhanging branches of the trees.

10 It is an object of the present invention to provide a structure of this character having its handle portion so mounted as to be swung downwardly out of the way, the handle, when in lowered position, constituting a means for 15 engaging a notched segment for the purpose of holding the lever and the parts controlled thereby against movement.

With the foregoing and other objects in view which will appear as the description 20 proceeds, the invention resides in the combination and arrangement of parts and in the details of construction hereinafter described and claimed, it being understood that changes in the precise embodiment of the invention 25 herein disclosed may be made within the scope of what is claimed without departing from the spirit of the invention.

In the accompanying drawings the preferred form of the invention has been shown.

30 In said drawings,

Figure 1 is a side elevation of a notched segment to which the present improvements are applied, the handle portion of the lever being shown lowered into engagement with 35 the segment.

Figure 2 is a section on line 2-2, Figure 1, the lever being shown in elevation.

Figure 3 is a view similar to Figure 2 showing the lever extended upwardly to 40 permit shifting thereof.

Referring to the figures by characters of reference, 1 designates a segment adapted to be attached to the frame of a cultivator or the like, a portion of which has been indicated at 2, this segment being formed with 45 a series of notches 3 radiating from a center 4 where a lever 5 is fulcrumed. This lever has a handle portion 6 hingedly connected thereto at 7 and that portion of the handle joined 50 to the lever is formed with an arcuate fin 8.

This fin is so proportioned that when the handle is disposed in alinement with the lever as shown in Figure 3, the end of the fin is spaced from the notched segment and said lever is permitted to swing about its 55 fulcrum 4. By swinging the handle 6 laterally and downwardly as shown, for example, in Figures 1 and 2, the fin 8 will enter the adjacent notch 3. Thus the lever will be locked against movement relative to the segment. Furthermore, the handle will be lowered so that it will not become caught in overhanging branches of trees when the improvements are used on orchard cultivators 60 and the like.

What is claimed is:

1. In a cultivator or the like, the combination with a notched segment, of a lever mounted to swing relative to the segment, a 70 handle hingedly connected to the lever and foldable downwardly onto the segment, and an arcuate notch engaging element concentric with the pivot of the handle and rotatable with the handle about said pivot into and out of engagement with the segment 75 when the handle is lowered and raised respectively.

2. The combination with a segment having notches, of a lever mounted to swing relative to the segment, a handle hingedly connected thereto and foldable downwardly onto the segment, and an arcuate fin carried by the handle and concentric with the pivot thereof, said fin being movable with the handle into engagement with a notch in the segment 80 when the handle is folded and out of said notch when the handle is in alinement with the lever.

In testimony that I claim the foregoing 85 as my own. I have hereto affixed my signature.
